ATTORNEYS

UNITED STATES PATENT OFFICE.

MENNO H. DAVIS, OF ALBION, MICHIGAN.

AUXILIARY SEAT.

Application filed January 3, 1922. Serial No. 526,555.

To all whom it may concern:

Be it known that I, MENNO H. DAVIS, a citizen of the United States, residing at Albion, county of Calhoun, State of Michigan, have invented certain new and useful improvements in Auxiliary Seats, of which the following is a specification.

This invention relates to improvements in auxiliary seats.

10 The main object of the invention is to provide an improved auxiliary seat which may be formed largely of wire, is light in weight, simple and economical to produce, may be collapsed in compact form, and quickly 15 erected and engaged with a chair or other support.

Further objects, and objects relating to structural details, will definitely appear from the detailed description to follow.

20 I accomplish the objects of my invention by the devices and means described in the following specification. The invention is clearly defined and pointed out in the claims.

A structure which is a preferred embodiment of my invention is clearly illustrated in the accompanying drawing, forming a part 25 of this application, in which:

Fig. I is a perspective view of my improved auxiliary seat erected, shown suspended on the back of a chair, the chair back being shown conventionally by dotted lines.

30 Fig. II is a perspective view of my improved seat collapsed.

Fig. III is a detail view with the back and 35 side members extended, the same being shown in this position in order to better show the structure thereof.

Fig. IV is an enlarged detail view on a line corresponding to line 4-4 of Fig. I, 40 showing structural details.

Fig. V is an enlarged detail sectional view on a line corresponding to line 5-5 of Fig. I.

In the drawing similar reference characters refer to similar parts throughout the 45 several views, and the sectional views are taken looking in the direction of the little arrows at the ends of the section lines.

Referring to the drawing, 1 represents the 50 back of a chair with my improved seat mounted thereon.

I provide a U-shaped seat frame disposed so that the cross portion 2 of the frame constitutes the front of the seat and the arms 55 3 the sides of the frame. This frame is

formed of heavy wire or rod. The ends 4 of the arms 3 are folded inwardly upon themselves, as shown, and the bight portions of the folds, being upwardly offset, provide ears 5. Cross pieces 6 and 6' are secured 60 to the side members, preferably by spot welding, the cross pieces 6 being arranged in spaced pairs to receive the rivets 7 for the seat bottom 8, as illustrated. The seat bottom is of fibre board or the like and is 65 secured by these rivets.

The back comprises the side members 9, also formed of wire, and the side members have eyes 10 at their lower ends engaging the ears 5, so that the side members may be 70 folded forwardly upon the seat. The ends of the side members 11 are folded inwardly and their bight portions formed into hooks 12 adapted to engage over the support.

The cross pieces 6 and 6' are secured to 75 the side members, the cross pieces 6 being arranged in spaced pairs to receive the rivets 7 for the back 13, substantially the same as the rivets for the seat.

The seat is supported by the hangers 14 80 having eyes 15 at their lower ends engaged with the side members 3 of the seat frame and hooks 16 adapted to be engaged with the top bar 6 of the back, so that the seat is suspended in proper relation to the back. 85 The side members 17 are also formed of wire, the wire having an eye 18 at one end engaging the side members and being bent into a rectangular frame, the hangers being spot-welded thereto, so that the side members are supported in upright position when the hangers are engaged.

The tray 19 is provided with hooks 20 which are adapted to be engaged over the top pieces 21 of the side members, thereby 95 supporting the tray, the tray also constituting a tie member for the side members so that a child occupying the seat cannot spring the same out.

With the parts thus arranged, the side 100 members and hangers may be folded upon the seat, the tray arranged thereon and the back collapsed upon the tray. The structure is quite light in weight and is simple and economical to produce. It also is very strong 105 and durable.

Having thus described my invention, what I claim as new and desire to secure by Letters Patent, is:

1. In an auxiliary seat, the combination of 110

a **U**-shaped seat frame disposed so that the cross portion thereof constitutes the front member of the seat and the arms the side members, the ends of the arms being folded inwardly parallel to the side members, the bights of the folds being upwardly offset providing ears, back side members having eyes at their lower ends engaging said ears, the upper ends of said side members being 5 folded inwardly, the bight portions being conformed into hooks adapted to be engaged over a support, cross bars disposed in spaced pairs connecting said back side bars and the side members of said seat, seat and back 10 boards secured to said cross bars by rivets engaged between the pairs of bars, and seat hangers having eyes at their lower ends engaging the side members of the seat frame to be collapsed thereon and having hooks at 15 their upper ends adapted to be detachably engaged with one of the cross bars of the back.

2. In an auxiliary seat, the combination of a **U**-shaped seat frame disposed so that the cross portion thereof constitutes the front member of the seat and the arms the side members, the ends of the arms being folded inwardly parallel to the side members, the bights of the folds being upwardly offset 20 providing ears, back side members having eyes at their lower ends engaging said ears, the upper ends of said side members being folded inwardly, the bight portions being conformed into hooks adapted to be engaged over a support, and seat hangers having eyes at their lower ends engaging the side members of the seat frame and hooks at their upper ends adapted to be 25 detachably engaged with the back side members whereby said seat hangers may be col-

lapsed upon the seat and the back collapsed upon said seat hangers.

3. In an auxiliary seat, the combination of a **U**-shaped seat frame disposed so that the cross portion thereof constitutes the front 45 member of the seat and the arms the side members, the rear ends of the side members having upwardly offset ears, back side members having eyes at their lower ends engaging said ears, the outer ends of said side 50 members hooked to be engaged with a support, cross bars disposed in spaced pairs connecting said back side bars and the side members of said seat, seat and back boards secured to said cross bars by rivets engaged 55 between the pairs of bars, and seat hangers having eyes at their lower ends engaging the side members of the seat frame and having hooks at their upper ends adapted to be engaged with one of the cross bars of the back. 60

4. In an auxiliary seat, the combination of a **U**-shaped seat frame disposed so that the cross portion thereof constitutes the front member of the seat and the arms the side members, the rear ends of the side members having upwardly offset ears, back side members having eyes at their lower ends engaging said ears, the outer ends of said side 65 members hooked to be engaged with a support, cross bars connecting said back side 70 bars and the side members of said seat, seat and back boards secured to said cross bars, and seat hangers having eyes at their lower ends engaging the side members of the seat frame and having hooks at their upper ends 75 adapted to be engaged with one of the cross bars of the back.

In witness whereof I have hereunto set my hand and seal.

MENNO H. DAVIS. [L.S.]
